United States Patent Office.

JAMES W. AIKIN AND JOHN H. STONE, OF PHILADELPHIA, PENNSYLVANIA.

Letters Patent No. 70,676, dated November 12, 1867.

IMPROVED MOTH-PROOF CASE.

The Schedule referred to in these Letters Patent and making part of the same.

TO ALL WHOM IT MAY CONCERN:

Be it known that we, JAMES W. AIKIN and JOHN H. STONE, of the city of Philadelphia, in the State of Pennsylvania, have invented a new and useful improvement in Moth-Proof Cases; and we do hereby declare that the following is a full, clear, and exact description of the construction and operation of the same, reference being had to the accompanying drawing, and to the letters of reference marked thereon.

The object of our improvement is to produce a sheet-metal case for receiving and preserving a lady's muff, cape, and other furs from access or damage by moths; and our invention consists in the combination of two or more concentric cylindrical apartments connected together by an annular bottom plate, the central cylinder being made of perforated sheet metal or wire gauze, and provided with a like perforated cover and a perforated diaphragm, and also opening through the bottom plate of the case, so as to admit of its being readily corked up and cemented air-tight from the outside of the case; and the outer cylinder being provided with a cap which is made to slip accurately over its upper end, and the joint then made air-tight by means of an elastic band-ring of vulcanized gum sprung over the same after the furs are inserted, all substantially as hereinafter described.

Referring to the drawing, A is the central cylinder, B the external cylinder, and C an intervening cylinder. The central cylinder A is made of perforated sheet metal, or of wire gauze, has a slip-cap, a', and a diaphragm, a'', of the same material. Its lower end opens into a circular recess, b', in the centre of the bottom of the case, as represented in the drawing, which recess b' is adapted for a cork stopper and cement, (as indicated by the faint lines,) so that it can be readily closed up air-tight when the case is put in use. The external cylinder B forms the outside of the case, has a close bottom and sides, and a close-fitting cap, b'', which slips on over its upper end. The band-ring b''' is cut transversely off from a tube of vulcanized gum, thus producing a ring which can be easily sprung around over the joint formed around the outside of the cylinder B by the lower edge of the cap b'', when the cylinder is to be closed air-tight, as shown in the drawing. The intervening cylinder C is shorter than the cylinder B, is left fully open at its upper end, and is fixed vertically to the annular bottom of the case, as represented in the drawing.

The case is prepared and used in the following manner: A lump of gum-camphor is first enclosed in the perforated cylinder A; the lady's muff is then slipped down around the cylinder A, and her cape and other smaller furs placed in the annular chamber or space which is between C and B. The cap b'' is now applied, and the elastic band-ring b''' then sprung around over the joint formed by the said cap b'', and the outside of the cylinder B, as represented in the drawing. The case is now laid upon its side, and, after remaining thus with its open bottom exposed to the air for an hour or two, for the purpose of causing a general circulation of the camphorated air through the furs, the opening b' in the lower end of A is to be corked up tightly, and then cemented over with wax, so as to close it air-tight, thus enclosing the said furs securely in a permanent manner in an atmosphere thoroughly impregnated with the camphor, effectually destroying the life of the moth, if present, and preventing any subsequent vitalization of any of the eggs of the insect which may be in the furs. This is a very easily operated, inexpensive, and effective moth-proof case for a lady's furs.

What we claim as our invention, and desire to secure by Letters Patent, is confined to the following, viz:

We claim a sheet-metal moth-proof case for a lady's furs, having the perforated central cylinder A, and the recess b', in combination with the cylinder B and the elastic band-ring b''', the said parts being constructed, arranged, and combined to operate together substantially as and for the purpose described.

JAMES W. AIKIN,
JOHN H. STONE.
